CLAIM

The ornamental design for a pole-mounted sensor, as shown and described.

DESCRIPTION

FIG. 1 is a top, front, right perspective view of a pole-mounted sensor, showing our new design;

FIG. 2 is a right side elevational view thereof;

FIG. 3 is a front elevational view thereof;

FIG. 4 is a left side elevational view thereof;

FIG. 5 is a back elevational view thereof; and,

FIG. 6 is a top plan view thereof.

The broken lines shown on the pole-mounted sensor depict portions of the article that form no part of the claimed design. The broken lines showing a pole illustrate environmental subject matter that forms no part of the claimed design.
